WINDOW CONSTRUCTION

Charles Jansen, Brooklyn, N. Y., assignor to
Nelson J. Edge, Jersey City, N. J.

Application March 8, 1945, Serial No. 581,604

7 Claims. (Cl. 20—53)

1

The present invention relates to a window construction and refers more particularly to a window comprising a window frame and pane elements tiltably supported in said frame on substantially horizontal axes extending laterally of said frame.

An object of the present invention is to provide a window of the above type with weatherstrip means.

Another object is to provide means for tilting one or more of said pane elements, the means being operable by a single actuating lever or the like and operative on said pane elements at both ends of the latter, the means further being operative to tilt pane element to which it is connected by the same amount and at the same time.

Yet another object is that, if, through abuse or other accident, the tilting means becomes damaged in such a way as to be wholly inoperative, the pane elements will by gravity assume a vertical, closed position.

A further object is to provide means associated with said tilting means and actuated by the same actuating means for actuating said weatherstrip means into sealing relation with said window frame after said pane elements have been actuated into substantially vertical and closed relation, and for actuating said weatherstrip means out of said sealing relation previous to tilting said pane elements.

Another and further object is that the sealing action of said weatherstrip means shall constitute a lock means preventing relative motion between said pane elements and said window frame.

Still another object of the invention is to provide a window frame in which the four elements constituting the sides of the rectangular frame shall be disconnectable from one form for convenience and economy in shipping.

Other objects will in part be obvious therefrom and in part will be pointed out as the description proceeds.

In the accompanying drawing, in which is shown one of the various possible illustrative embodiments of this invention:

Figure 1 is a front elevation of a window embodying the present invention.

Figure 2 is a sectional view on the line 2—2 of Figure 1.

Figure 3 is a sectional view on the line 3—3 of Figure 4.

Figure 4 is a sectional view on the line 4—4 of Figure 3.

Figure 5 is a sectional view on the line 5—5 of Figure 4.

2

Referring now in detail to the drawings, my improved window 10 comprises the substantially rectangular window frame 10A, the latter comprising the side members 10B, 11, header 12 and sill 13, all preferably of channel sheet metal construction. The side members 10B, 11 have surfaces 13A, 13B finished square with their length, and portions 13C projecting beyond said square finished portions and formed with slots 13D. The portions 13C project through slots 13E in header 12 and sill 13. Wedges 13F are driven into slots 13D to draw the square finished portions 13A, 13B against the sill 13 to detachably connect the three sides together into the substantially rectangular window frame 10A. The frame can thus be shipped completely knocked down at a considerable saving of shipping space, and assembled on the job.

The bars 14 are formed with the slots 14A extending longitudinally thereof, and bolts 14B extending perpendicularly from side members 10B extend through slots 14A and carry the nuts 14C, whereby the bars 14 are vertically slidably mounted in the side members 10B. Bars 14 are further formed with the slots 14D, which are so located relative to one another as to constitute a rack 15.

A circular gear 16 is rotatably mounted on stud 17 on side member 10B and is operatively connected to handle 18, and to bar 14, the teeth of gear 16 engaging the rack 15, so that rotation of handle 18 rotates gear 16 to slide bar 14 relative to side member 10B.

Bars 14 are formed with a plurality of long openings 19 and comprise the racks 20 along one side of the openings and facing thereinto.

The pane holding elements or sash 20A comprise at each end the side bars 20B having an elongated body of modified H cross section, the latter comprising a bight or U-shaped portion 20C and a guide ledge portion 20D extending in a common plane with and integral with one of the arms 20E of the U portion 20C.

Gears 21 engage the racks 20 of bars 14 in the side members 10B, 11, and are securely mounted on the pivot shafts 22 of pane holding elements 20A, the shafts 22 being journaled in the side members 10B, 11 at 22A. Firmly mounted on gears 21 are the parti-cylindrical segments 23 forming part of the window locking and weatherstrip actuating mechanism 24 to be described hereafter.

The window panes 25 are made up of two sheets of glass separated by spacer strips 25A. Straps 26 rotatably connect the pivot shafts 22 to the other arms 26A of the U-shaped portions

20C opposite the arms 20E in the plane of the guide ledge 20D. The panes 25 are frictionally and resiliently held in the U-shaped portions 20C by the insulating material 27 located under compression between panes 25 and portions 20C.

The following means are provided for causing simultaneous and equal motion in the same direction of the bars 14 mounted in each of the side members 10B of window frame 10A.

A shaft 28 is rotatably journaled as at 28A in both side members 10B, 11, extending therebetween inside the sill 13. Gears 29 keyed to shaft 28 near each end thereof engage the racks 30 of bars 14, so that sliding actuation of the bar 14 illustrated in Figures 3, 4 and 5 and on the left of Figure 1 rotates shaft 28 and thus slidingly actuates the similar bar 14 on the right of Figure 1 by the same amount in the same direction at the same time.

The locking and weather strip mechanism 24 previously mentioned comprises the sleeve bearing 31 and the sleeve 32 slidably mounted on pivot shaft 22 and in bearing 31. Segment 23 is formed with the arcuate cam slot 33, and pin 34 mounted in sleeve 32 extends radially therefrom and into slot 33. The weatherstrips 35, of L cross section, are rigid and equal in length to the height of the pane elements 20A and are firmly mounted by means of their integral collars 36 on the sleeves 32. Resilient insulating material 37 extends around the foot of the L of weatherstrips 35 and in sliding contact with the guide ledge 20D. Thus sleeves 32 and weatherstrips 35 are slidable as units longitudinally of pivot shafts 22 and pane elements 20A. Since outer surfaces of weatherstrips 35, extending for a substantial distance on both sides of the axis of pivot shafts 22 and of sleeve 32, are in sliding surface contact with the inner surfaces 20F of guide ledge 20D, said surface 20F extending substantially longitudinally of pane holding elements or sash 20A, relative rotation between weatherstrip and sash is prevented, and rotation of sleeve 32 is effective to rotate the pane elements 20A. In the illustrated position of Figure 5, weatherstrips 35 extend into the weatherstrip grooves 38 formed in side members 10B, 11, and extending from header 12 to sill 13 and facing into the window opening.

The window operates by rotating handle 18 clockwise of Figure 1, thus rotating gears 16 in the direction of the arrow of Figure 3 and clockwise of Figure 4, sliding bars 14 upward, both bars 14 of the window moving together as previously explained. Upward movement of bars 14 causes rotation of gears 21 counterclockwise of Figure 3 and in the direction of the arrow of Figure 4. Segments 23 being fast to gears 21 will move with them. Pins 34 cannot rotate as they are fast to sleeve 32 which are fast to weatherstrips 35 which are engaged in grooves 38. Therefore pins 34 and sleeves 32 with them will be cammed to the right of Figures 4 and 5, disengaging weatherstrips 35 from grooves 38. Because the pivotal suspension of pane elements 20A is higher than the center of gravity thereof, and also because the axis of rotation of the pane elements is located inwardly of the window relative to the center of mass of the pane holding elements in all positions thereof, gravity will bias pane holding elements 20A towards a substantially vertical, closed position, so that they are at all times resisting the tilted position illustrated in Figure 2. Pins 34 being fixed against rotation relative to pane elements 20A will thus resist rotation away from the vertical position of pane

elements 20A until cam slots 33 of segments 23 have forced them to the extreme right position, that is to the right end of the cam slots 33 of segments 23, and further rotation of handle 18 causing further rotation of gears 21 and segments 23 will rotate pins 34 about the axis of pivot shafts 22 to tilt pane elements 20A and thus open the window as illustrated in Figure 2. It is evident from the above that pins 34 function as cam followers.

In closing the window, counterclockwise rotation of handle 18 is first effective to progressively release pane holding elements 20A to the action of gravity to close the same, after which further rotation of segments 23 will cam pins 34 to the left of Figures 4 and 5 to return weatherstrips 35 into grooves 38 to simultaneously lock the window and seal it against the entry of the weather.

It will thus be seen that there is provided a device in which the several objects of this invention are achieved, and which is well adapted to meet the conditions of practical use. As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, what I claim as new and desire to secure by Letters Patent is:

1. In a window construction of the type comprising a substantially rectangular window frame comprising side, header and sill members, and a substantially rectangular pane holding element, said pane holding element having pivot shafts journaled therein and in said side members on a substantially horizontal axis, said pane holding element being tiltable on said pivot shafts from a substantially vertical, closed position to an open position and said axis being so located relative to said pane holding element as to cause the latter to be biased toward closed position by gravity, the combination with said side members, said pivot shafts and said pane holding elements, of a bar slidably mounted in one of said side members and comprising a tooth rack, means for slidingly actuating said bar in said side member, a sleeve slidably mounted on said pivot shaft, a gear coaxially attached to said pivot shaft and operatively engaged by said rack, a part cylindrical segment firmly connected to said gear, coaxial therewith and with said sleeve, a pin mounted on said sleeve and extending radially therefrom, said segment projecting over a substantial portion of said sleeve and having a cam slot therein mating with said pin, said cam slot being inclined toward the pane holding element, and a weatherstrip firmly mounted on said sleeve and slidingly engaging said pane element and fixed against rotation relative thereto, whereby sliding actuation of said bar rotates said gear and segment to first slide said sleeve and weatherstrip from a sealing and locking engagement with said side member in the closed position of said pane holding element, and thereafter to tilt said pane element against gravity to open said window, and sliding actuation of said bar in the opposite direction first progressively releases said pane holding element to the action of gravity to close the same and thereafter slides said sleeve and weatherstrip into a sealing and locking engagement of the latter with said side member.

2. In a window of the type comprising a substantially rectangular window frame comprising side, header and sill members and a substantially rectangular pane holding element, pivot shafts supporting said pane holding element and in said side members on a substantially horizontal axis and fixed against axial movement relative thereto, said pane holding element being tilttable on said pivot shafts from a substantially vertical, closed position to an open position, and said axis being so located relative to said pane holding element as to cause the latter to be biased toward closed position by gravity, the improvement comprising the combination with said side members and said pivot shafts, said side members being formed with vertical grooves facing into the frame opening, of a first means securely and coaxially mounted on one of said pivot shafts for rotation therewith, a part cylindrical segment firmly connected to said means and formed with a cam slot, a sleeve slidably mounted on said pivot shaft, a pin mounted on said sleeve and extending therefrom into said slot, said segment extending over a substantial portion of said sleeve and said slot being inclined toward said pane holding element, a weatherstrip firmly mounted on said sleeve and slidingly engaging said pane holding element and fixed against rotation relative thereto, and actuating means operatively engaging said first means to rotate the same, whereby operation of said actuating means rotates said first means and segment to first slide said sleeve and weatherstrip from a sealing and locking engagement with the groove of its side member in the closed position of said pane element, and thereafter to tilt said pane element to open said window, and reverse operation of said actuating means first progressively releases said pane holding element to the action of gravity to close the same and thereafter draws said sleeve and weatherstrip into a sealing and locking engagement of the latter with the groove of said side member.

3. A weatherstripping and actuating member for window sash mounted on pivot shafts comprising a sleeve slidable and rotatable on the sash pivot shaft, and a rigid weatherstrip firmly connected to said sleeve, said weatherstrip comprising a surface extending for a substantial distance on both sides of the axis of said sleeve and located for sliding contact with a longitudinally extending surface of said sash.

4. Actuating and weatherstripping means for windows of the type comprising a sash mounted for tilting movement about a substantially horizontal pivot shaft, said shaft being so located relative to said sash as to bias the latter to closed, substantially vertical position by gravity, comprising a first means mounted securely on said shaft for rotation therewith, a sleeve slidably and rotatably mounted on said shaft, weatherstrip means securely mounted on said sleeve and slidingly engaging said sash and fixed against rotation relative thereto, and interengaging guide means operatively connecting said first means and said sleeve, said guide means being so con-

structed and arranged as to provide successive sliding and rotation of said sleeve from rotation of said first means in one direction, and to provide successive opposite rotation of said sleeve and sliding thereof from rotation of said first means in the opposite direction.

5. Actuating and weatherstripping means for window sash mounted on a pivot shaft in a frame, comprising the combination of a first means mounted securely on said shaft for rotation therewith, a sleeve slidably and rotatably mounted on said shaft, weatherstrip means securely mounted on said sleeve and slidingly engaging said sash and fixed against rotation relative thereto, and interengaging guide means operatively connecting said first means and said sleeve, said guide means being so constructed and arranged as to provide successive sliding and rotation of said sleeve from rotation of said first means in one direction, and to provide successive opposite rotation of said sleeve and sliding thereof from rotation of said first means in the opposite direction.

6. Actuating and weatherstripping means according to claim 5, said means further comprising means operatively associated therewith and so constructed and arranged relative to said sleeve and weatherstrip means as to inhibit rotation of said sleeve and weatherstrip means until the completion of axial movement thereof during the actuation of said first means in one direction, and as to inhibit axial movement of said sleeve and weatherstrip means until the completion of rotation thereof during reverse actuation of said first means.

7. A weatherstripping and actuating member for window sash mounted on pivot shafts comprising a sleeve slidable and rotatable on one of the sash pivot shafts, and a rigid weatherstrip firmly connected to said sleeve, said weatherstrip engaging a projection on the sash when said sleeve is mounted on said pivot shaft, said weatherstrip and said projection being so constructed and arranged relative to each other and to the axis of said pivot shaft as to prevent relative rotation between sash and weatherstrip at all times.
